US00D791510S

(12) **United States Design Patent** (10) Patent No.: **US D791,510 S**
(45) Date of Patent: **** Jul. 11, 2017**

(54) **NECK PILLOW**

- (71) Applicant: **EDMACO INTERNATIONAL S.A.**,
Luxembourg (LU)
- (72) Inventor: **Paolo P. J. Renna**, Monterubbiano FM
(IT)
- (73) Assignee: **EDMACO INTERNATIONAL S.A.**,
Luxembourg (LU)
- (**) Term: **15 Years**
- (21) Appl. No.: **29/560,151**
- (22) Filed: **Apr. 4, 2016**

(30) **Foreign Application Priority Data**

- Oct. 2, 2015 (EM) 002808071-0001
- (51) LOC (10) Cl. **06-09**
- (52) U.S. Cl.
USPC **D6/601**
